UNITED STATES PATENT OFFICE.

WILLIAM F. RITTER, OF CINCINNATI, OHIO.

ELECTRIC-ARC LAMP.

SPECIFICATION forming part of Letters Patent No. 678,517, dated July 16, 1901.

Application filed March 21, 1901. Serial No. 52,181. (No model.)

To all whom it may concern:

Be it known that I, WILLIAM F. RITTER, a citizen of the United States of America, and a resident of Cincinnati, in the county of Hamilton and State of Ohio, have invented certain new and useful Improvements in Electric-Arc Lamps, of which the following is a specification.

This invention relates to certain improvements in electric lamps, and has for its object to provide an arc-lamp of a simple and inexpensive nature and of a strong and durable construction having improved means for supporting the carbon electrodes in place and for connecting the same in the electric circuit and also provided with improved means for regulating the movement of the upper electrode.

The invention consists in certain novel features of construction, combination, and arrangement of the several parts of the improved lamp, whereby certain important advantages are attained, and the device is made simpler, cheaper, and otherwise better adapted and more convenient for use, all as will be hereinafter fully set forth.

The novel features of the invention will be carefully defined in the claims.

In the accompanying drawings, which serve to illustrate my invention, Figure 1 is a view showing the improved lamp in side elevation and on a reduced scale. Fig. 2 is an enlarged sectional view taken vertically through the lamp in substantially the plane indicated by the line *a a* in Fig. 4. Fig. 3 is a partial sectional view taken vertically through the lamp in the plane indicated by the line *b b* in Fig. 4. Fig. 4 is a horizontal section taken through the upper part of the lamp in the plane indicated by the line *c c* in Fig. 1. Fig. 5 is a sectional view taken horizontally through the lamp in the plane indicated by the line *d d* in Fig. 3. Fig. 6 is a fragmentary sectional view taken through the lower frame-plate in the plane indicated by the line *e e* in Fig. 5 and showing the means for supporting the lower carbon. Fig. 7 is a view similar to Fig. 4, but showing the upper-carbon holder in transverse section. Fig. 8 is an enlarged sectional detail view taken through the lower electrode-holder in the plane indicated by the line *f f* in Fig. 2.

As shown in the drawings, the improved lamp has a frame formed of an upper circular plate 1, a central annular plate 2 of diameter equal to plate 1, and a lower plate 3 of less diameter than plates 1 and 2, the said plates being held together in the frame by vertical rods or bolts 4, three in number and arranged equidistant from each other. 55 The said rods or bolts 4 have reduced and screw-threaded lower ends 5, which are passed through the central frame-plate 2 and have their lower extremities screwed into the lower frame-plate 3. Nuts 6 on said rods or 60 bolts support the plate 2, as shown in Fig. 2.

The lower carbon electrode is supported below the lamp-frame by means of an arm 7, which depends below the lower plate 3 and is formed at its upper end with a reduced and 70 screw-threaded part 8, which is passed through a lug 9 on said plate 3, as shown in Figs. 1, 5, and 6, and is properly insulated therefrom. A nut 10 is screwed on said part 8 above plate 3 and serves to hold the arm 7 to the 75 frame. The lower end of the arm 7 is bent laterally and carries a forked part 11 central beneath the lamp-frame, and between the forks of said part 11 is held for vertical movement a sleeve 12, adapted to receive in its 80 hollow or bore the lower electrode *x* and having at its upper part an annular flange 13, provided with a screw 14, by means of which the electrode is held in said sleeve.

On the sleeve 12 is loosely held a washer or 85 annulus 15, which rests on the forked part 11, and above said washer is arranged a spiral spring 16, which has engagement under the flange 13 and serves to hold the sleeve pressed up from the part 11. A cap 17 is screwed on 90 the open lower end of the sleeve 12 in order to prevent the electrode when loose from falling out of the sleeve, and said cap acts as a stop to prevent excessive upward movement of the sleeve under pressure of said spring 95 and also prevents entry of air into the globe. A screw 18 is passed through the forks of the part 11, as shown in Figs. 1, 2, and 8, and serves to prevent the sleeve from slipping laterally from between the forks.

The flange 13 of the sleeve forms a gallery whereon rests a globe 20, the flange having a circular raised part 19 on its upper face to take into the lower open end of the globe

and prevent lateral movement thereof. The globe 20 incloses the lower and upper electrodes x and y and at its upper end has engagement inside of an annular bead 21 on the under side of the lower frame-plate 3. The upward pressure of the spring 16 is exerted in such a way as to hold the globe 20 securely in place between the flange 13 and the said lower frame-plate 3.

10 Within the frame of the improved lamp are arranged parallel guides 23 23, spaced apart and extended vertically at the central portion of the lamp-frame, being held at their upper ends in openings in the upper frame-plate 1, through which openings the guides are slid down through the central space in the annular central frame-plate 2 until their lower ends rest upon the lower frame-plate 3. The guides 23 are formed, by preference, as 15 shown in Fig. 2, from metal tubing, having in their lower ends plugs 24, held in place by crimps 25, bent in the tubing and formed with threaded apertures to receive screws 26, which are passed from beneath through the lower frame-plate 3 and into said plugs to hold the guides 23 in position in the frame. 20

A slide 27 is arranged for vertical sliding movement between the guides 23 and has arms 28 recessed to fit between the said guides 25 and is provided at opposite sides and between said arms 28 with brushes 29, formed from sheet metal and arranged to press upon the guides in order to insure a perfect electrical communication between the guides and the 30 slide 27. The slide has also at its central part a clip 30, loosely held to the slide by means of a central screw 22, so as to be adapted for a certain extent of movement, and said clip has a screw 31, by means of which the 35 upper electrode y is held to said clip. The lower frame-plate 3 has a central opening, through which the upper electrode is passed down into the globe 20, as seen in Figs. 2 and 3.

40 At one side of the frame is located a resistance of a well-known kind, herein shown as supported on cleats 32, adjustably held on two of the rods or bolts 4 and carrying screws 33, whereon are held insulators 34, around which 45 are passed resistance-coils 35. One end of the resistance has connection with one binding-post 36, insulated on the lamp-frame, while from the other end of the resistance a conductor extends to a solenoid-coil 37. The 50 coil 37 is wound on a sleeve or tube 38, the ends of which are screw-threaded to receive the heads 39 and 40, between which the coils are held, and one of the threaded ends of said sleeve or tube 38 is made to extend beyond 55 the head 40 and has threaded engagement, as shown at 41 in Fig. 3, with the central frame-plate 2 through an opening in which the said extended end of the sleeve or tube is passed.

60 42 indicates the core of the solenoid, movable vertically in the tube or sleeve 38 and also formed with an axial hollow or bore, through which is passed a stem 44, to which

the core is adjustably held by means of a screw 43. The upper end of the stem 44 carries a piston 45, which is arranged to work in a dash-pot 46, loosely held by a screw 47 on the upper frame-plate 1, while the lower end of said stem has threaded engagement with a circular or disk-like part 48, guided at its center on a pin 49, extended up from the lower frame-plate 3, the opposite or inner edge portion of said disk 48 having, as shown in Fig. 3, engagement under one edge of an annular clutch member 50, through which the upper electrode y is passed. The disk 48 is 80 provided with a plurality of openings 48^a in its edge portion and adapted to be engaged by the lower end of stem 44, so that in case the threads in one opening become worn the stem may be inserted in another opening. 85 The clutch member 50 is loosely held and is capable of tilting movement when lifted at one edge by the part 48, and when so moved its edges have engagement with opposite sides of the electrode in such a way as to firmly 90 grip the electrode and hold it against downward movement. When the clutch member is not uplifted by the part 48, the electrode y will be released from the gripping action of said clutch member and will be permitted to 95 fall freely by gravity.

The circuit from the binding-post 36 after traversing the resistance and the solenoid-coil 37 is grounded on the frame of the lamp, so that from said frame it is carried through 100 the guides 23 and slide 27 to the upper electrode y . The lower electrode x is in electrical communication with the arm 7 through the sleeve 12 and the forked part 11, and from the nut 10, by means of which the arm 7 is 105 held in place beneath the frame-plate 3, a conductor 52 is extended up within the frame to another insulated binding-post 51, as shown in Fig. 1.

In operation when the current is flowing in 110 the lamp the circuit is from the binding-post 36 through the resistance-coils 35 to the solenoid-coil 37 to the lamp-frame, guides 23, slide 27, and to the upper electrode y , and thence through the lower electrode x , the 115 sleeve 12, part 11, arm 7, and wire 52 to the binding-post 51. The solenoid acts in a well-known way to check and regulate the downward movement of the upper electrode, so that the arc is preserved, and should the arc 120 be broken the solenoid, being deenergized, will at once permit the core 42 to fall and through the connected parts will release the upper electrode from the clutch member 50, so that the arc may be reestablished. 125

The construction of the improved lamp as above described is very simple, strong, and inexpensive, the guides 23 and brushes 29 traversing the same affording a very simple and most effective means for insuring electrical connection with the upper carbon without in any way hindering the necessary movements of the electrode and the loosely-held clip 30 affording a degree of adjustability to 130

said upper carbon, so as to prevent it from being stopped in its descent by slight irregularities or by wedging of its lower end. The means for supporting the lower electrode are also much improved in that they throw but little shadow and permit of readily removing and replacing the electrode and globe in cleaning and trimming and also in that the sleeve 12 permits the employment of a much longer lower carbon than is ordinarily provided in lamps, so that by adjusting the carbon up in said sleeve the lamp may be made to burn a much longer time than has heretofore been possible. The annular bead 21 on the plate 3 also permits of using two sizes of globe on the lamp, one fitting within said bead and the other being larger and fitting outside the bead.

It will also be seen from the above description that the improved lamp is capable of some modification without material departure from the principles and spirit of the invention, and for this reason I do not wish to be understood as limiting myself to the precise form and arrangement of the several parts as herein set forth.

Having thus described my invention, I claim—

1. In a lamp, the combination of a frame having guides, a part adapted to carry an electrode and held for movement between the guides and a brush having its central portion secured to said part and having its arms extended at angles and arranged for sliding contact upon opposite sides of one of said guides to insure electrical connection of said electrode, substantially as set forth.

2. In a lamp, the combination of upper and lower frame-plates, tubes held in the upper frame-plate and having their lower ends rested on the lower frame-plate, plugs in the lower ends of the tubes, crimps in the tubes and holding said plugs in place, screws passed through the lower frame-plate and engaged with said plugs, the tubes being parallel and forming guides and a part adapted to carry an electrode and held for movement between said guides, substantially as set forth.

3. In a lamp, the combination of a frame having guides, a slide having arms grooved for engagement with the guides, brushes carried by the slide for engagement with the guides, a clip adapted to carry an electrode, and a screw passed centrally through the clip and having threaded engagement with the slide to hold the clip for pivotal movement on the slide, substantially as set forth.

4. In a lamp, the combination of a frame formed of three frame-plates, a dash-pot held on the upper frame-plate, the central frame-plate being formed with an opening, means for supporting an electrode, a solenoid comprising a coil wound on a tube, said tube having threaded engagement in the opening of the central frame-plate, a hollow core in said

tube, a stem passed through the hollow of the core and having adjustable engagement therewith, the upper part of the stem having a piston working in said dash-pot and the lower end of the stem depending below the central frame-plate and a clutch member actuated from said stem and arranged for engagement with the electrode, substantially as set forth.

5. In a lamp, the combination of a frame, a solenoid, an annular clutch member loosely mounted and arranged to receive an electrode passed through its central opening, a stem actuated from the solenoid, a part having threaded connection with said stem and having engagement under one side of the clutch member for tilting the same and means for guiding the said part when moved, substantially as set forth.

6. In a lamp, the combination of a frame, a solenoid, an annular clutch member loosely mounted and arranged to receive an electrode passed through its central opening, a stem actuated from the solenoid and having a threaded lower end, a pin on the frame, and a disk-like part guided at its central portion on said pin and having at one side engagement with the threaded lower end of the stem, its other side having engagement under the clutch member for tilting the same, substantially as set forth.

7. In a lamp, the combination of a frame, an arm extended down from the frame, a sleeve carried by the arm and adapted to receive an electrode and also adapted for endwise movement, means for holding the electrode adjustably in said sleeve and a spring arranged for engagement with said sleeve for pressing the same elastically upward, substantially as set forth.

8. In a lamp, the combination of a frame, an arm extended down from the frame, a sleeve carried by the frame for endwise movement, and formed with an annular flange at its upper part, the sleeve being adapted to receive an electrode, means for holding the electrode adjustably in said sleeve, a washer loose on the sleeve and rested on the arm, and a spring coiled on the sleeve between said washer and the upper flange of the sleeve and arranged for pressing the sleeve elastically upward, substantially as set forth.

9. In a lamp, the combination of frame-plates spaced apart, rods having reduced and screw-threaded end portions passed through one of the plates and screwed into another of said plates, and nuts held on the threaded reduced ends of the rods for engagement under the first-named plate, substantially as set forth.

Signed at Cincinnati, Ohio, this 13th day of March, 1901.

WILLIAM F. RITTER.
